ADJUSTABLE MOUNTING FOR FLUE CLEANERS AND THE LIKE

Filed August 28, 1925 2 Sheets-Sheet 1

A diagram showing a gear assembly. A dashed circle represents the outer boundary of the assembly. Inside this circle, there is a smaller circle with a dashed outer boundary. The number '14' is placed near the top left of the inner dashed circle. The number '15' is placed near the top right of the inner dashed circle. The number '17' is placed near the bottom right of the outer dashed circle.

UNITED STATES PATENT OFFICE.

RALPH W. J. STEBEL, OF LUCKEY, OHIO, ASSIGNOR OF ONE-HALF TO WM. E. HESSMAN, OF LUCKEY, OHIO.

ADJUSTABLE MOUNTING FOR FLUE CLEANERS AND THE LIKE.

Application filed August 28, 1925. Serial No. 53,199.

This invention relates to apparatus for universally mounting a working instrument or device and is particularly useful in supporting a fluid pressure operated flue cleaner.

An object of the invention is to provide a simple and efficient apparatus for supporting a working tool so that the position of the instrumentality may readily and conveniently be adjusted in both a vertical and horizontal plane.

Further objects of the invention will hereinafter appear and the invention is shown by way of illustration in the accompanying drawings, in which—

Fig. 1 is a top plan view of the apparatus; Fig. 2 is a vertical, sectional elevation of the apparatus shown in Fig. 1; and Fig. 3 is an end view of the apparatus.

Referring to the drawings, the apparatus comprises an upright rectangular frame having sets of legs 1 and 2 which consist of I-beams and are suitably connected together as by rivets at their upper ends by sets of cross braces 3 and 4. Movable vertically within the upright frame is a rectangular carriage frame consisting of pairs of I-beams 5 and 6 suitably connected together as by rivets and braced in any usual or well known manner. Suitably secured to the ends of the I-beams 6 of the carriage frame are U-shaped guide members 7 which embrace the adjacent legs of the upright frame so that in this manner the vertical movement of the carriage frame is guided relative to the upright frame.

For raising the carriage frame a rotatable shaft 8 is supported in bearing blocks 9 and 10 on top of the cross braces 4 of the upright frame and cables 11 are wound around the shaft 8 for a portion of their length, extend over pulleys 12 connected to the braces 3 of the upright frame and are connected at their ends to hook bolts 13 which are fixed to the carriage frame. It will thus be seen that rotation of the shaft 8 in one direction winds the cables thereon and in this manner hoists the carriage frame to the desired vertical position, and rotation of the shaft 8 in the opposite direction serves to permit the carriage frame to lower itself by its own weight.

In order to rotate the shaft 8, a gear 14 is fixed to the shaft and meshing with the gear 14 is a pinion 15 supported on one end

of a stub shaft 16 to which a sheave 17 is fixed at the opposite end. An endless cable 18 may be trained over the sheave 17 so that the operator may manually rotate the sheave 17 in the desired direction for raising or lowering the carriage frame to the proper vertical position.

Movable laterally along the I-beams 5, is a carriage having U-shaped housings 19 which enclose the I-beams or rails 5 and for supporting the carriage on the rails 5 pairs of rollers 20 are arranged within the housings 19 and engage the rails 5. In this instance there is a pair of rollers in each housing and, as indicated, an opposed roller of each pair is connected by a shaft 21 which is fixedly connected thereto. Provided on the ends of the rollers of each pair are sprockets 22 which are connected by chains 23. It will thus be seen that rotation of the shaft 21 conjointly drives the rollers of both sets.

For driving the shaft 21 a bevel gear 23 is fixed thereto and meshing with the gear 23' is a gear 24 to which is connected an operating crank handle 25. Enclosing the gears 23' and 24 and forming a support for the gear 24 is a housing 26 which is fixed to one of the U-shaped housings 19 by a pin 27 which extends through the housing 19 and is held in place by a cotter pin 28. A pin 29 extends through the opposite housing 19 and is held in position by a cotter pin 30.

Supported on the U-shaped housing member 19 is a working tool which, in this instance, is a device for cleaning the flues of boilers and the like. The flue cleaner consists of an elongate cylinder 31 which is held in place by U-bolts 32 which extend through apertures in the housing member 19 and are engaged by nuts 33. The opposite ends of the cylinder 31 are closed by plugs 34 and arranged within the cylinder 31 is a piston 35 having a piston rod 36 which is adapted to carry at its outer end a brush or other working instrument, buffer springs 37 being arranged at opposite ends of the cylinder for receiving the blow of the piston 35.

The piston 35 is actuated by fluid pressure which may be steam or compressed air and which is admitted alternately to the opposite ends of the cylinder 31 through a pipe 38. The passage of fluid to the cylinder 31 may be controlled by any suitable valve mecha-

nism within the valve box 39, in this instance a manual control being provided by means of a handle 40 operatively associated with the valve mechanism. Pressure fluid may be supplied to the valve box 39 through the connection 41 and the exhaust 42 is positioned on the opposite side of the valve box, as shown.

It will readily be apparent that the position of the carriage frame in a vertical plane may be adjusted by pulling on the endless cable 18 in order to raise or lower the frame so as to position the piston 36 of the working tool in proper vertical relation. Thereafter the proper lateral position of the piston rod 37 may be controlled by manipulating the crank handle 25 to move the carriage frame laterally in one direction or the other. In this manner complete freedom of movement is obtained and the working tool may be readily and conveniently positioned accurately with respect to the work.

While I have shown and described a construction which is the best form known to me at the present time, it is to be understood that numerous changes in details of construction, arrangement and application may be effected without departing from the spirit of the invention, especially as defined in the appended claims. It is further to be understood that the invention is not limited solely for use in connection with a flue cleaner because its application is much more comprehensive and may be admirably used to advantage in a variety of situations.

What I claim as new and desire to secure by Letters Patent, is:—

1. In an apparatus of the class described, the combination of a rectangular upright

frame, a carriage frame in said upright frame, U-shaped guides on said carriage frame engaging said upright frame for guiding the movements of said carriage frame, means on the upper portion of said upright frame for raising said carriage frame, said means including a rotatable shaft and cables connecting said shaft and carriage frame, a carriage on said carriage frame and movable laterally thereon, pairs of rollers for supporting said carriage, means for connecting said rollers for conjoint operation and manually operable means for driving said rollers.

2. In an apparatus of the class described, the combination of a carriage frame having spaced parallel rails, a carriage movable on said rails and having U-shaped housings embracing said rails, rollers in said housings, for supporting said carriage and movable on said rails and means for conjointly driving said rollers thereby to propel said carriage in one direction or another.

3. In an apparatus of the class described, the combination of a carriage frame having parallel spaced rails, a carriage having U-shaped housings enclosing said rails, pairs of rollers in said housings engaging said rails for supporting said carriage, a shaft fixed to opposed rollers and rotatable therewith, a chain and sprocket connection between the rollers of each pair, and means for rotating said shaft for conjointly driving said rollers thereby to propel said carriage in one direction or another.

In testimony whereof I have hereunto signed my name to this specification.

RALPH W. J. STEBEL.
